ROLLING MILL GUIDE

Stevenson Findlater, McKeesport, Pa., assignor
to National Tube Company, a corporation of
New Jersey

Application September 24, 1936, Serial No. 102,417

6 Claims. (Cl. 80—51)

This invention relates to rolling mill guides and more particularly to guides for metal work-pieces, such as bars, shells, pipes, tubes, blooms or billets, that are entering or leaving a rolling mill.

In the art of rolling metals, a great deal of difficulty has been experienced in guiding the various sized work-pieces. This has necessitated providing a large stock of different sized guides which not only is quite expensive but takes up a large amount of floor space in the mill. In addition, a great loss of time and labor has been involved in changing the guides to accommodate the section being rolled. Further, it has been particularly difficult to provide suitable guides for reversing mills employing a plurality of "passes".

It is accordingly among the objects of my invention to provide an efficient rolling-mill guide which is readily adjustable to accommodate sections that vary over a wide range of dimensions, and one which is, at the same time, well adapted for use on mills of existing design.

Another object is the provision of a device of the class described which is inexpensive to install and maintain.

The foregoing and other objects will be apparent after referring to the drawings, in which:

Figure 1 is a plan of the device of the invention.
Figure 2 is a side elevation.
Figure 3 is an enlarged end elevation.
Figure 4 is an enlarged sectional view on the line IV—IV of Figure 3.
Figure 5 is a plan of a modified form of the device of the invention.
Figure 6 is an end elevation, partly in section.
Figure 7 is a sectional view on the line VII—VII of Figure 6.

A preferred embodiment of my universal guide consists of a train of two-high guide roll units, each unit consisting of a top roll 3 and a bottom roll 4 having a plurality of complementary tapering grooves X around their peripheries, the train being disposed at either the entrance and/or the exit side of a rolling mill A. The rolls 3 and 4 are mounted in bearings 5 which are mounted on suitable side-frame members 6 and 6*. The shaft 7 of each of the rolls 3 and 4 carries a keyed gear 8 which meshes with an individual worm-gear 9, the latter being secured to a shaft 10 that is rotatably mounted in bearings 11 on the side-frame members 6 and 6*. This shaft 10 is driven by a conveniently disposed motor 13 through a reduction gear 14 and flexible couplings 15.

According to the preferred embodiment, which

readily lends itself to the tubular arts, the grooves are half-round, but they may, of course, be of other shape, such as square, rectangular, oblong, oval, etc. The axes of the grooves X are in a vertical plane, perpendicular to the longitudinal axis of the rolls 3 and 4 so that the center line of the groove will not change as the roll is rotated.

The top and bottom rolls 3 and 4 are positioned so that the half-round grooves X form between them a round groove to guide the work-piece, the rolls being positioned so that the grooves are of the same size in each complementary pair of the train. The rolls 3 and 4 are so disposed that the center line of their respective grooves is in the same plane as the center line of the pass of the rolling-mill, which, as previously mentioned, is indicated at A. The number of grooves X in the rolls 3 and 4 should be the same as the number of working passes B in the rolling mill A, each being in line therewith. The length of the train of rolls 3 and 4 and their number are such that guiding area is provided at suitable intervals throughout the length of the work-piece.

In operation, when the size of the work-piece being processed on the mill is changed, the motor 13 is energized which acts to rotate the shaft 10 through the flexible couplings 15, and gear reduction unit 14, whereupon the gears 8 and 9 are synchronously rotated to partially rotate in like manner the rolls 3 and 4. The amount of partial rotation of the rolls 3 and 4 is determined by the size of the groove desired. Thus, all of the rolls will be turned the same part of a revolution and the size of their respective grooves will be changed the same amount.

Referring to Figures 5, 6 and 7 of the drawings, a modified form of the invention is shown as comprising a pair of peripherally grooved rolls 3 which are transversely movable into alignment with any of the passes of the rolling-mill A. The rolls 3 of Figures 5, 6 and 7 are provided with single tapering grooves X in lieu of the plurality of grooves in the rolls 3 of Figures 1 through 4, and are rotated in the same manner as the latter.

According to this modification the shafts 10 which carry this pair of rolls 3 are square in section while the rolls are provided with correspondingly shaped central apertures 20. These rolls 3 are provided with lateral extensions 21 which carry enlarged boss portions 22. A yoke 23 is provided for connecting these boss portions 22. A shaft 24 is connected to the yoke 23 and extends

- through the side-frame member 6^a. The extended end of this shaft 24 is threaded, as shown at 26. An extension 27 is carried by the side-frame member 6^a and has an aperture through which the threaded end 26 of the shaft 24 extends. The extension 27 on the side-frame member 6^a carries a nut 29 which is in threaded engagement with the threaded end 26 of the shaft 24. This nut 29 carries a worm gear 30. A suitably driven shaft 31 is disposed beneath the worm gear 30 and carries a worm 32 which meshes therewith. From the foregoing it will be seen that the rotation of the shaft 31 will adjust the rolls 3 into and out of any lateral position.
- 15 While I have shown and described several specific embodiments of my invention, it will be understood that I do not wish to be limited exactly thereto, since various modifications may be made without departing from the scope of my invention, as defined by the following claims.
- I claim:
1. A rolling mill guide comprising a plurality of pairs of rotatable complementary guide-forming rolls, each of said rolls having a plurality of grooves of gradually increasing diameter around its periphery, whereby a plurality of series of guide passes of variable size are formed between said rolls, and means for synchronously rotating said rolls.
  2. A rolling mill guide comprising a pair of rotatable complementary guide-forming rolls, each of said rolls having a groove of gradually increasing diameter around its periphery, and means for moving said rolls axially.

3. In combination with a rolling mill, a stationary guide device constructed and arranged to present a guiding surface to a work-piece during the movement of the latter, said guide device comprising a pair of rotatable complementary guide-forming rolls, each of said rolls having a groove of gradually increasing diameter around its periphery, and means for synchronously rotating said rolls.

4. In combination with a rolling mill, a guide device comprising a pair of rotatable complementary guide-forming rolls, each of said rolls having a groove of gradually increasing diameter around its periphery, means for synchronously rotating said rolls, and means for moving said rolls axially.

5. In combination with a rolling mill, a stationary guide device constructed and arranged to present a guiding surface to a work-piece during the movement of the latter, said guide device comprising a pair of rotatable complementary guide-forming rolls, each of said rolls having a groove of gradually increasing diameter around its periphery.

6. A rolling mill guide, comprising a plurality of pairs of rotatable complementary guide-forming rolls, each of said rolls having a plurality of grooves of gradually increasing diameter around its periphery whereby a plurality of series of guide passes of variable size are formed between said rolls.

STEVENSON FINDLATER.
